UNITED STATES PATENT OFFICE.

KARL ROTH, OF TERRE HAUTE, INDIANA.

LEAK-PROOF STRIP FOR METAL ROOFING.

1,076,065.

Specification of Letters Patent.

Patented Oct. 21, 1913.

Application filed March 25, 1913. Serial No. 756,703.

To all whom it may concern:

Be it known that I, KARL ROTH, a citizen of the United States, residing at Terre Haute, in the county of Vigo and State of Indiana, have invented certain new and useful Improvements in Leak-Proof Strips for Metal Roofing, of which the following is a specification.

In the manufacture of sheet metal roofing 10 special effort is made to provide joints between the metal sheets which shall resist the action of capillary attraction and thereby prevent water from passing between the overlapping edges of the sheets. To attain 15 this end a large variety of different crimpings along the edges of each individual sheet are employed which mesh or register with crimps of like formation in the adjacent sheets, all tending to make water-tight 20 joints when the sheets are placed in position. These special arrangements in connection with sheet metal roofing add to the cost of such manufacture. In case regular corrugated iron is used, which is used to a large 25 extent to cover the roofs of buildings, the sheets must be lapped for several corrugations so that considerable material is lost to each square laid, and this wide overlapping of the edges does not always provide water- 30 tight joints from the fact that the water oftentimes moves along between the contacting surfaces of the overlapping sheets, induced by capillary attraction, making the plainest sort of a corrugated roof expensive, and one 35 that is liable to leak at any time.

This invention relates to an individual metal joint or strip, formed independently of the metal sheets that form the roof, these metal joints being provided with a centrally located strip corresponding to the crimping in the metal sheets, thereby making it specially desirable to use in connection with roofing already in use.

The object of the invention consists in the 45 provision of a sheet metal strip for sealing the joint between the overlapping edges of sheet metal roofing, thereby insuring that the joints between the sheets of metal roofing will be made proof against leakage.

A further object of the invention is to provide a sheet metal joint for sheet metal roofing which is independent of the sheets, and which will be cheap to manufacture in view 50 of its disconnection from the metal sheets forming the roof, and one that can be used

in connection with standard roofing material wherein crimpings and corrugations are employed.

I accomplish the above objects of the invention by means of the construction illustrated in the accompanying drawings, forming a part hereof, in which—

Figure 1 is a fragmentary detail view in cross section of the sheathing of the roof showing the overlapping edges of the two sheets of the ordinary corrugated metal roofing, and showing my independently formed joint in operative position. Fig. 2 is a fragmentary detail view in perspective of my proposed independently formed metal joint, 60 showing its character and formation when used in connection with the old and well known corrugated metal sheets. Fig. 3 is a fragmentary detail view in cross section of the roof showing the overlapping edges of a well-known sheet metal roofing wherein V-shaped corrugations or crimpings are employed, and showing my independently formed joint or strip in operative position therewith. Fig. 4 is a fragmentary detail 65 perspective view of the independently formed sheet metal strip showing the V-shaped corrugation therein.

Referring to the drawings, 10 represents the ordinary sheathing of buildings that is 85 nailed to the rafters 11. Fig. 1 illustrates the application of old and well known corrugated metal sheets which are extensively used in forming roofs for buildings, said sheets herein being designated by the 90 numerals 12 and 13. As now employed the edges of these corrugated sheets are overlapped to the extent of from two to three of the corrugations in order to reduce the 95 possibility of leakage to a minimum. This wide overlapping of the sheets consumes quite an additional amount of material to the square and does not entirely render the joint tight against the passage of water for the reason heretofore explained.

I am aware of the fact that there are numerous sheet metal roofings on the market wherein each plate is provided with a certain kind of corrugation or crimping along the edges, in order to form air spaces and the like, all tending to produce a waterproof seam between the overlapping edges of the sheet metal roofing. Moreover, these extra crimpings not only require special machines which add to the cost of production, but are 100 105 110

not capable of being used in connection with or in the repairing of roofs that are already in use.

- My improved metal joint, which is formed 5 independently and may be sold independently of sheet metal roofing, is formed of a flat strip of sheet metal 20, and may be of the same character as that employed in manufacturing the metal sheets of the roof.
- 10 Each metal strip is provided with a centrally arranged longitudinally extending corrugation 21 which is properly formed to correspond to and engage the corrugation formed in the roof. This centrally formed 15 corrugation 21 adds additional strength and reinforces the overlapping edges of the sheets 12 and 13 so that the usual wood strip, which is inserted beneath this particular corrugation to prevent the corrugation 20 from being flattened when the nails are passed through the sheets, is dispensed with. The edges of the strips 20 are bent into a vertical position to form the shoulders 22 so that a channel or gutter 23 is formed on 25 each side of the corrugation 21 and the shoulders 22, these channels adapted to confine and carry away such water as may gain access thereto after passing between the overlapping edges of the plates 12 and 13.
- 30 The strips 20 containing the double channels 23 have an advantage in that they may be laid either way beneath the overlapping edges of the plates 12 and 13, the only pre-requisite being that the corrugations 21 and 35 shoulders 22 must project upwardly from the sheathing 10, but it is readily seen that the cost of the strip 20 can be still further reduced by merely providing a single channel and a single shoulder 22 with the central 40 corrugation 21, omitting the rest of the stock from the line A—A in Fig. 2. While this would cheapen the cost of manufacture it will be noted that the strips 20 must of necessity be laid one way with respect to the 45 overlapping edges of its sheets in order to get the benefit derived from the single channel 23 remaining in the strip. It will be noted that the shoulders 22 do not touch the metal sheets 12 and 13 so that an intervening space remains, to resist the action of 50 capillary attraction. Figs. 3 and 4, while showing a different style of crimping, practically illustrate the same construction as shown in Figs. 1 and 2, which has heretofore been described, and it is deemed unnecessary 55 to go into a detailed description thereof.
- Having thus fully described my said invention, what I desire to secure by Letters Patent, is—
1. A sheet metal roof comprising a plurality of sheet metal sections, longitudinally extending corrugations formed in each section adjacent to the side edges of said sections, the overlapping adjacent edges of the sections adapted to permit the corrugations 65 in one section to engage the corrugations in the adjacent section, a strip formed independently of said sections and adapted to lie beneath the overlapping edges of said sections, a corrugation formed in said strip to 70 engage the corrugations in the sections, and shoulders formed of the side edges of the strip to raise said edges above the floor of the strip. 75
2. A sheet metal roof comprising a plurality of sheet metal sections, longitudinally extending corrugations formed parallel with the side edges of said sections, the overlapping adjacent edges of the sections permitting the corrugations in one section to register with the corrugations in the adjacent section, an independently formed strip adapted to be inserted beneath the overlapping edges of the sections, shoulders formed along the edges of the strip, and means 80 formed in the strip to engage the corrugations in the sections for holding said strip in operative relation with said sections. 85

In witness whereof, I have hereunto set my hand and seal at Indianapolis, Indiana, 90 this 26th day of February, A. D. one thousand nine hundred and thirteen.

KARI ROTH. [L. S.]
